UNITED STATES PATENT OFFICE.

WILLIAM EVANS, OF BIRMINGHAM, CONNECTICUT.

RISE-AND-FALL JACQUARD MECHANISM.

SPECIFICATION forming part of Letters Patent No. 498,912, dated June 6, 1893.

Application filed February 27, 1893. Serial No. 463,948. (No model.)

To all whom it may concern:

Be it known that I, WILLIAM EVANS, a citizen of the United States, residing at Birmingham, in the county of New Haven and State 5 of Connecticut, have invented certain new and useful Improvements in Rise-and-Fall Jacquard Mechanisms, of which the following is a specification, reference being had therein to the accompanying drawing.

- 1c My invention relates to what are known in the art as rise and fall Jacquard mechanisms. In a Jacquard mechanism of this class, the vertical hooked wires are moved up and down in the opening and closing of the sheds, by 15 what are known usually as a griff and a hook plate, which are moved simultaneously in opposite directions, the griff rising and the hook-plate descending in the opening of a shed, and the griff descending and the hook-plate 20 plate ascending in the closing of a shed. It has been proposed heretofore to so operate the griff and hook-plate as that the hook-plate shall be caused to dwell or momentarily rest at or about the time of the complete closing of 25 the shed, this dwell or rest in the movement of the hook-plate having been secured by devices which are shown and described in United States Letters Patent to George W. Stafford and C. H. Poland, No. 420,119, granted January 28, 30 1890. The reasons for thus operating the hook-plate are fully set forth in the specification of the said patent, to which reference may be made, and need not be repeated herein. It has been proposed heretofore, also, to operate 35 the griff and hook-plate so as to occasion either a dwell of both, or a dwell of the hook-plate alone after the shed has been fully opened, the object in the first case being to give the shuttle fair opportunity to pass completely 40 through the shed while the opposite planes thereof remain separated sufficiently to give it unobstructed passage, and in the second case the object being to provide against the shuttle becoming lifted from contact with the 45 shuttle-race, or diverted from its proper line of movement, in consequence of the rising of the bottom plane of the shed before the shuttle has completed its flight from one side of the loom to the other.
- 50 My invention has for its main object to provide in a simple and practical manner for se-

curing dwells in the movements of the parts at both the time of the closing of the shed and while the shed is fully opened.

Another object is to provide by simple and 55 convenient means of adjustment for enabling the action of the griff and hook-plate to be variously modified.

My invention consists in certain novel, useful, and improved combinations of parts, all 60 as hereinafter is made clearly to appear, and it first will be fully described with reference to the accompanying drawing, and then will be particularly pointed out and precisely defined in the claims appended to this specification and making a part hereof.

The accompanying drawing shows in side elevation a portion of a rise and fall Jacquard mechanism of usual construction, with my invention applied thereto, enough of the said 70 mechanism being represented to render clearly apparent the nature and relations of my invention.

At 1 is shown the frame-work of the Jacquard mechanism, at 2 a supporting beam, at 75 3 the usual operating lever, the same being actuated in known and suitable manner from one of the rotating shafts of the loom to which the Jacquard mechanism is applied.

At 4 is shown the pivotal support for lever 3, 80 the said support being secured to the beam 2.

At 5 is shown the griff, and at 6 is shown the hook-plate.

All of the foregoing, and such of the details necessary to a complete and operative Jacquard mechanism as are not shown in the accompanying drawings, are or may be of any known or suitable construction.

At 7 is a rocker which is pivoted at 8 to the end-piece 9 forming part of the frame-work 1. 90

At 10 is a link or connection which at one end thereof is connected pivotally with one arm 11 of the rocker 7 and at the other end thereof is connected pivotally with the griff 5, and at 12 is a second link or connection 95 which at one end is connected pivotally with the other arm 13 of the rocker 7 and at the other end thereof is connected pivotally with the hook-plate 6. The arm 11 also has connected therewith pivotally one end of a link 100 or connection 14, the other end of which is connected pivotally with one arm 15 of a

second rocker 16. The other arm 17 of the said rocker 16 has connected pivotally therewith one end of a link or connection 18 which at its other end is connected pivotally with the inner end of the operating lever 3. Through the described connections the said operating lever 3 transmits motion to the griff 5 and hook-plate 6. The slot 19 in the arm 15 of the second rocker 16 enables the link or connection 14 to be pivotally connected with the said arm at any desired radial distance from the axis on which the said rocker turns, and thus provides for varying the throw transmitted through the link or connection 14, and thereby varying the size of the opening of the shed.

The points at which the links or connections 11 and 12 are connected with the rocker 7 are at any desired and suitable angular distance apart, this distance depending in part upon whether both the griff and hook-plate or only one of them shall be caused to dwell as the said rocker is moved. I have shown the said distance as being less than one hundred and eighty degrees, inasmuch as in the mechanism illustrated I contemplate producing by the action of the said rocker a dwell of only one of the parts actuated therefrom. The parts intermediate the operating lever 3 and the rocker 7 will ordinarily be proportioned and arranged in such manner that as the said rocker is caused to near the end of its stroke in one direction, and thereby reaches the position which it occupies at the time of one extreme in the shed-formation, one of the points of pivotal connection of the links or connections 11, 12, therewith will reach or pass slightly beyond a dead center, this occasioning a dwell in the movement of the corresponding actuated part. Preferably, the arrangement, &c., are such as to cause the hook-plate thus to dwell at the time of the closing of the shed, in order to secure the mode of operation and results which are set forth in Letters Patent No. 420,119, hereinbefore mentioned. With the object in view of securing a dwell of both the griff and the hook-plate at the other extreme of the shed-formation, which, in this instance, is when the shed is open, the second rocker 16 ordinarily is connected and arranged by me in the manner shown in the drawing to cause the pivotal connection between the same and the link or connection 14 to reach or pass slightly a dead center at the time when the shed has been opened fully.

Each of the links or connections 10, 12, 14 and 18 is made variable in length. A suitable construction thereof is shown in the drawing, in which each of the said links or connections is made in two parts. These parts are slotted where they overlap each other, as at 101, and through the slots pass bolts 102 for holding them adjustably together. By making the said links or connections variable in length I am enabled to effect readily desired or necessary adjustments thereof, and

to vary the action of the griff and hook-plate in important respects. For example, by lengthening the links or connections 14 and 18, the position of the rocker 16 may be so changed as not to allow the point of pivotal connection between it and the link or connection 14 to pass the top center, and thus less than the full attainable amount of dwell at the time of the open shed may be obtained. In proportion as the lengthening is continued the amount of dwell will be reduced. If this lengthening be continued to a sufficient extent, the dwell may be prevented altogether from occurring. By the lengthening of the link or connection 14, and the shortening of the links or connections 10 and 12, the position of the rocker 7 may be changed similarly so as to reduce the amount of the dwell of the hook-plate when the shed is closed, and if this lengthening is continued to a sufficient extent the dwell will disappear. Should it be desired at any time to raise or lower the Jacquard harness, which heretofore has been accomplished, usually, by raising and lowering the entire Jacquard mechanism, it is necessary only to adjust or vary in obvious manner the lengths of the links or connections 10 and 12. By effecting adjustment of the link or connection 12, the height of the lower plane of the open shed may be regulated, and thereby the said lower plane may be made to bear properly upon the shuttle race of the loom.

The rocker 16 will usually be mounted on one end of a rock-shaft 169, the latter being extended through to the other end of the Jacquard mechanism, where the connections intermediate the said shaft and the griff and hook-plate will be duplicated, as will be understood.

What I claim is—

1. The combination with the griff and hook-plate of a rise and fall Jacquard mechanism, links or connections connected therewith, and a rocker to which said links or connections are connected, of a link or connection connected with the rocker for moving the same, a second rocker having the point of connection of the last-mentioned link or connection therewith adapted to reach or pass slightly a center in the turning of the second rocker, to occasion a dwell of both the griff and hook-plate at one extreme of the shed-formation, and means for operating the second rocker, substantially as described.

2. The combination with the griff and hook-plate of a rise and fall Jacquard mechanism, links or connections connected therewith, and a rocker having one of the points of connection of the said links or connections therewith adapted to reach or pass slightly a center in the movement of the rocker, for the purpose of occasioning a dwell of the corresponding actuated part at one extreme of the shed-formation, of a third link or connection whereby to move the said rocker, a second rocker having the point of connection of the third link or connection thereto adapted to

reach or pass slightly a center, for the purpose of occasioning a dwell of both the griff and the hook-plate at the other extreme of the shed-formation, and means for operating the second rocker, substantially as described.

3. The combination with the griff and hook-plate of a rise and fall Jacquard mechanism, links or connections of variable length connected with both thereof, a rocker with which 10 said links or connections are connected also, and means for actuating the said rocker, whereby by varying the operative length of the links or connections the Jacquard harness may be raised and lowered and the height of 15 the lower plane of the open shed may be regulated substantially as described.

4. The combination with the griff and hook-plate of a rise and fall Jacquard mechanism, links or connections of variable length connected with both thereof, and a rocker having 20 one of the points of connection of the said links or connections therewith adapted to reach or pass slightly a center in the movement of the rocker, for the purpose of occasioning a dwell of the corresponding actuated 25 part at one extreme of the shed-formation, of a third link or connection also variable in length whereby to move the said rocker, and means for moving the said third link or connection, whereby by varying the operative length 30 of the links or connections the Jacquard harness may be raised and lowered, and the height of the lower plane of the open shed may be regulated, and also the amount of the 35 aforesaid dwell may be varied, substantially as described.

5. The combination with the griff and hook-plate of a rise and fall Jacquard mechanism, links or connections of variable length connected with both thereof, and a rocker having 40 one of the points of connection of the said links or connections therewith adapted to reach or pass slightly a center in the movement of the rocker, for the purpose of occasioning a dwell of the corresponding actuated 45 part at one extreme of the shed-formation, of a third link or connection also variable in length whereby to move the said rocker, a second rocker having the point of connection 50 of the last-mentioned link or connection therewith adapted to reach or pass slightly a center in the turning of the second rocker, to occasion a dwell of both the griff and the hook-plate at one extreme of the shed-formation, a 55 link or connection of variable length connected with the second rocker for the purpose of moving the same, and means for moving the last-mentioned link or connection, substantially as described.

plate at the other extreme of the shed-formation, and means for moving the said second 55 rocker, substantially as described.

6. The combination with the griff and hook-plate of a rise and fall Jacquard mechanism, links or connections of variable length connected with both thereof and a rocker having 60 one of the points of connection of the said links or connections therewith adapted to reach or pass slightly a center in the movement of the rocker, for the purpose of occasioning a dwell of the corresponding actuated 65 part at one extreme of the shed-formation, of a third link or connection also variable in length whereby to move the said rocker, a second rocker having the point of connection 70 of the last-mentioned link or connection therewith adapted to reach or pass slightly a center in the turning of the second rocker, to occasion a dwell of both the griff and the hook-plate at the other extreme of the shed-formation, a link or connection of variable length 75 connected with the second rocker for moving the same, and means for moving the link or connection last-mentioned, substantially as described.

7. The combination with the griff and hook-plate of a rise and fall Jacquard mechanism, links or connections connected therewith, and a rocker having one of the points of connection of the said links or connections adapted 80 to reach or pass slightly a center in the movement of the rocker, for the purpose of occasioning a dwell of the corresponding actuated part, of a link or connection of variable length 85 connected with the said rocker for moving the same, a second rocker having the point of 90 connection of the said link or connection therewith adapted to reach or pass slightly a center in the turning of the second rocker, to occasion a dwell of both the griff and the hook-plate at one extreme of the shed-formation, a 95 link or connection of variable length connected with the second rocker for the purpose of moving the same, and means for moving the last-mentioned link or connection, substantially as described. 100

In testimony whereof I affix my signature in presence of two witnesses.

WILLIAM EVANS.
